UNITED STATES PATENT OFFICE.

GUSTAF OLSON, OF CHICAGO, ILLINOIS, ASSIGNOR OF ONE-HALF TO WILLARD M. McEWEN, OF CHICAGO, ILLINOIS.

COMBINED FLUID PUMP AND MOTOR.

1,316,855.

Specification of Letters Patent. Patented Sept. 23, 1919.

Application filed June 4, 1917. Serial No. 172,869.

To all whom it may concern:

Be it known that I, GUSTAF OLSON, a citizen of the United States of America, and a resident of Chicago, county of Cook, and 5 State of Illinois, have invented certain new and useful Improvements in Combined Fluid Pumps and Motors, of which the following is a specification.

This invention relates to improvements in 10 combined fluid pumps and motors of the type wherein a plurality of vanes, shiftably mounted on a rotor eccentrically journaled within the stator, are normally held with the ends thereof in close proximity with the 15 walls of said chamber as said vanes move therethrough during the rotation of said rotor.

The main object of this invention is to 20 provide improved means for adjusting the vanes on the rotor, so as to vary the proximity of the vane ends with the walls of the pressure chamber.

An illustrative embodiment of this invention is shown in the accompanying drawings, in which:

Figure 1 is an end elevation partly sectional of the device.

Fig. 2 is a transverse sectional elevation of the device.

30 The device herein illustrated is the same as that shown and described in my copending application Serial No. 119,462, filed September 11, 1916. As in said copending application the device is illustrated as an 35 air compressor or pump, and is hereinafter so described, but it will be understood that it is equally suitable for use with other fluids as a compressor or pump, or that it may be used as a fluid operated motor by an obvious 40 reversal of some of the parts.

In the construction herein illustrated, a casing 1, supported on a standard 2, is provided with a chamber 3 which is a composite formation of two eccentrically arranged 45 bores, the centers of which are designated 5 and 7 respectively. The wall of the chamber therefore comprises two opposed arcuate parts 4 and 6.

The rotor comprises a disk-shaped member 8 having a hub portion 9 keyed to the shaft 10 and having an axially disposed an-

nular flange 11. The shaft 10 is journaled in a bearing 12 formed on the casing 1 with its axis coincident with the center 5, whereby the rotor is mounted so that the periphery 55 of the flange 11 fits with the wall 4 and provides a space 13 between the periphery of said flange and the wall 6. A ring-shaped member 14 is secured to the flange 11, so as to overlap the inner and outer periphery 60 thereof and provide a projecting flange which is rotatably supported in a circular recess 15. The recess 15, which is formed in the casing 1 with its center coincident with the center 5 of the wall 4, provides a 65 circular shoulder portion against which the projecting flange part of the ring 14 fits. The ring 14 thus forms a closure for the space between the outer periphery of the flange 11 and the walls 4 and 6, and coacts 70 with the disk 8 and flange 11 to provide guideways for the vanes 16.

A plurality of vanes 16 are carried by the rotor, being shiftably mounted in the radially disposed slots 17 formed in the disk 8 75 and flange 11. These vanes are reciprocated in their respective slots through the action of the guide member 18, so that the ends thereof are urged into close proximity with the annular walls 6 as they are moved by 80 the rotor, the vanes being shifted outwardly as they move around the lower part of the chamber 13 and shifted inwardly as they are moved through the upper part of said chamber. 85

The guide member 18 is rotatably mounted on roller bearings 18.1 on a shaft or pin 19 carried by a plate 20, which together with a second plate or disk 21 forms a closure for the casing. The shaft 19 is disposed with its axis coincident with the center 7, thereby being eccentrically located with respect to the axis of the rotor. An annular groove 22 is formed in the face of the member 18, which is opposed to the rotor disk 8. Blocks or vane-bearings 23 are shiftably mounted in the groove 22 and are provided with circular openings 24 which receive fingers 25 formed on the vanes 16. This arrangement of the bearings 23 provides a rigid but shiftable pivotal support 90 for the inner ends of the vanes 16 and allows 95 100

for their swinging movement relative to the guide member 18 as they are rotated around the chamber 3.

The plate 20 is secured to the plate 21 by means of stud bolts 26, and the plate 21 is in turn attached to the casing 1 by means of suitable bolts 27, so as to form a fluid-tight seal for said chamber. Elongated holes 28 are formed in the plate 20 to receive the bolts 26 so that the plate 20 may be shifted relative to the plate 21 for the purpose of adjusting the eccentricity of the guide member 18 with respect to the rotor 8. This adjustment of the guide member 18 enables the obtention of a more nearly perfect contact of the vanes 16 with the wall 6 of the casing chamber. This adjustment is of material advantage for the reason that with the relation of these rotating parts definitely fixed within the casing it is extremely difficult to form all of said parts sufficiently accurate to insure an air tight fit of the ends of the vanes 16 with wall 4. With present adjustment such extreme care does not have to be exercised in the construction of the vanes and guide member, for now, after being assembled within the casing the plate 20 may be shifted to bring the vanes into proper contact with the wall 4.

30 The construction and arrangement of the rotor, the guide member 18, and closure 20—21, as herein illustrated, provide an annular compartment 31 between all of the parts inwardly of the inner periphery of the flange 11. This space is adapted to contain a quantity of oil which serves the double function of providing a lubricant for all the moving parts of the device and keeping them cool.

40 Inlet and outlet ports 29 and 30 are formed in opposite sides of the casing 1, so as to communicate with respectively opposite ends of the space 13.

In the construction herein shown, these 45 ports are axially disposed and located so as to connect with the ends of the chamber 13.

A series of fins 32 are formed on the exterior parts of the casing 1, which provide for the dissipation of heat created by the 50 operation of the device.

The operation of the device herein shown is as follows:

The shaft 10 is to be driven by a suitable source of power which may be connected to the usual shaft coupling 33. For following out the operation of the device, it will be assumed that the rotation is in the direction of the arrow 34.

The rotation of the rotor and the guide 60 member 18 about their eccentric centers 5 and 7 causes the vanes 16 to reciprocate so that as the vanes approach the right hand end of the space 13 (Fig. 1), they are caused to move out into contact with the

annular wall 6, and recede as they approach the left hand end of said space. As each of the vanes passes the annular opening 29, a vacuum is created, rearwardly thereof which is filled with air admitted through said inlet 29.

70 As each of the vanes approaches the outlet 30, the air in advance of each of said vanes is compressed and discharged through said outlet 30, as will be obvious.

When the parts are assembled in the casing chamber, the plate 20 is set so as to provide the desired adjustment of the vanes 16 with the wall 4. If the device is to be used for pumping air, the vanes usually require a positive contact of the vane ends with the wall. If a liquid is to be pumped, the vane ends do not need to contact with the wall 4. As the vanes wear on the ends the plate 20 may be shifted so as to take up the wear.

80 Although but one specific embodiment of this invention has been herein shown and described, it will be understood that numerous details of the construction shown may be altered or omitted without departing from the spirit of this invention as defined by the following claims.

85 I claim:

1. In a device of the class described, the combination of a casing having a chamber 95 formed therein, a rotor journaled in a bearing formed on one side of said casing having the periphery thereof fit, with the wall of said chamber and providing a space between said periphery and the remaining 100 portion of said chamber wall, a plurality of radially movable vanes mounted on said rotor, a guide member rotatably mounted in a bearing formed on the opposite side of said casing eccentrically of said rotor bearing, said guide member coacting with said vanes for normally holding the ends thereof in close proximity to said remaining part 105 of said chamber wall as they traverse said space, and means on said opposite side of said casing for adjusting the eccentricity 110 of the bearing of said guide member with respect to said rotor bearing so as to vary the proximity of said vane ends with said chamber wall.

115 2. In a device of the class described, the combination of a casing having a chamber formed therein, a rotor journaled in a bearing formed on one side of said casing having the periphery thereof fit with the wall 120 of said chamber and providing a space between said periphery and the remaining portion of said chamber wall, a plurality of radially movable vanes mounted on said rotor, a guide member rotatably mounted 125 in a bearing formed on the opposite side of said casing eccentrically of said rotor bearing, said guide member coacting with

said vanes for normally holding the ends thereof in close proximity to said remaining part of said chamber wall as they traverse said space, and a plate forming part of said 5 opposite side of said casing carrying said rotor bearing, said plate being shiftable so as to adjust the eccentricity of said guide member bearing with said rotor bearing, so as to vary the proximity of said vane ends with said remaining part of said chamber 10 wall.

Signed at Chicago this 31st day of May, 1917.

GUSTAF OLSON.
